UNITED STATES PATENT OFFICE

169,403

VEHICLE TRACTION CLEAT

John M. Westrate, Pleasant Ridge, Mich.

Application November 29, 1952, Serial No. 22,494

Term of patent 14 years

(Cl. D90—20)

To all whom it may concern:

Be it known that I, John M. Westrate, a citizen of the United States, residing at Pleasant Ridge, State of Michigan, have invented a new, original, and ornamental Design for a Vehicle Traction Cleat, of which the following is a specification, reference being had to the accompanying drawing, forming a part hereof.

Fig. 1 is a side elevational view of a vehicle traction cleat embodying my new design.

Fig. 2 is an edge elevational view; and

Fig. 3 is a top plan view.

I claim:

The ornamental design for a vehicle traction cleat, as shown.

JOHN M. WESTRATE.
